UNITED STATES PATENT OFFICE.

FREDERIC C. BILLINGS, OF HARTFORD, CONNECTICUT.

METAL-WORKING MACHINE.

SPECIFICATION forming part of Letters Patent No. 642,289, dated January 30, 1900.

Application filed October 25, 1899. Serial No. 734,705. (No model.)

To all whom it may concern:

Be it known that I, FREDERIC C. BILLINGS, a citizen of the United States, residing in Hartford, in the county of Hartford and State 5 of Connecticut, have invented certain new and useful Improvements in Metal-Working Machines, of which the following is a specification.

This invention relates to metal-working machines of that class having a reciprocatory tool and means for actuating said tool, and has for its object the provision of an improved head in a machine of the character described, said head carrying the tool-actuating devices and being formed in such a manner that it will strengthen the frame and serve as a bracing member between the upper ends thereof, whereby the machine is rendered very stiff and rigid and displacement of the 20 parts and shearing of the securing-bolts are obviated. To this end the head is provided with overhanging members which are fitted on the frame and which form, in connection with a central member, means for carrying the 25 tool-actuating devices, so that the parts constituting the operating mechanism may be fitted in place and secured in their proper positions on the frame as a unitary structure.

My invention is shown preferably applied 30 to drop-hammers, although it is not limited thereto, as it may be employed with various classes of machines in which the frame is subjected to strain or vibration by the impact of the tool.

35 In the drawings accompanying and forming part of this specification, Figure 1 is a perspective view of a drop-hammer embodying my invention. Fig. 2 is a side view of the upper part of the frame, one of the roll-supporting shafts being in section. Fig. 3 is a perspective view of the main part of a head constructed in accordance with my invention. Fig. 4 is a side elevation, partially in section; and Fig. 5 is a plan view of the head, partially 45 in section.

Like numerals and letters designate like parts in all the figures of the drawings.

In the drawings, 10 represents the base, to which the side frames or uprights 11 and 11' 50 are secured at their lower ends and between which the tool 12 is guided, said tool in the exemplification carrying a board 13, whereby

the same may be lifted by a pair of rolls 14 and 14', journaled in bearing-boxes 15 and 15', two of which, 15, are adapted to be moved toward and away from the others in the usual manner.

Usual caps 40, hinged to lugs 40' of head H, hereinafter described, are employed for securing the bearing-boxes in position on said head, and the usual rod 50 is provided for releasing the rolls either manually or automatically in a well-known manner.

Heretofore it has been the practice to mount the carriers containing these bearing-boxes independently of each other on the tops of the side frames or uprights of the machine and to secure them by bolts passing vertically through said parts, and frequent annoyance has been caused by the shearing or breaking 70 of the bolts, which has been due to the vibration or springing action of the frames or uprights when the machine is in operation and particularly when the hammer or other tool strikes an inclined piece of work and there- 75 by tends to wrench the uprights apart.

In the present construction the head carrying the bearings consists of a body, preferably a casting, rigidly secured in position between the tops of the frame or uprights by 80 one or more bolts passing transversely through both of said frames, which are in this manner clamped tightly against the central member of the head, the result being that the strain on the parts due to the action of the 85 machine is evenly distributed and thrown substantially upon the head, and as the bolts for retaining the head in position pass transversely through the uprights and not vertically, as heretofore, all tendency to shear or 90 break the same is practically overcome.

The roll 14 is carried on a shaft 16, having an eccentric 16', journaled in half-bearings 15 of the head, as clearly shown in Fig. 2, while the roll 14' is journaled on a shaft 17, 95 resting in boxes 15', which, as shown in Fig. 2, may be adjusted by the usual bolts. The bearings 15 are located in the side members 19 19' and in the usual hinged caps of the head, which is designated in a general way 100 by H and is provided with a central depending member 20, located between and resting against the uprights, said member 20 being preferably formed integral with the side mem-

- bers 19 and 19', although it may be attached thereto without departure from my invention, and having an aperture 21 to permit the passage of a lifting-board or other device 13.
5. Each of the side members 19 and 19' has at its under side a recess, such as 22, adapted to fit over the top of each side frame 11 and 11', and said central member 20 projects below the side members and serves as an abutment against which the upper ends of the side frames 11 and 11' may be brought to bear, as by means of bolts 23 and 24 and the nuts 23' and 24', respectively, as clearly shown in Figs. 4 and 5.
15. Each side frame or upright 11 11' is rabbed at 11², and the projection 11³ fits in a recess 22' in depending member 20, ribs or flanges 25 on said member 20 preventing displacement of the head vertically.
20. As will be understood, the tops of the uprights 11 11' fit in the recesses 22 of the head when the latter is placed in position, whereby said uprights will be brought into alignment with each other, while at the same time 25 the distance between them will be positively determined by the intervening central member 20, so that they will be properly spaced apart and the hammer will be truly guided when in operation. As will be evident, when 30 the frame of a drop-hammer is provided with a head as above described great rigidity will result, due to the fact that the parts are rigidly united, as shown, and consequently the evil effects due to the vibration of the frame 35 will be reduced to a minimum or entirely obviated.

While the usual lifting-rolls are shown as a type of tool-operating mechanism which may be employed, it is distinctly to be understood that the invention is not limited thereto, for other lifting mechanism may be used without departure therefrom.

Having described my invention, I claim—

1. In a machine of the class specified, the combination, with a tool, of frames between which the tool is guided; a head fitted to and having a projecting member located between and the sides thereof bearing against said frames; means passing outside of the head 45 for securing said head to the frames; and means carried by the head for actuating the tool.
2. In a machine of the class described, the combination, with a pair of side frames and a hammer, of a head having a depending member supported by and between and bearing against said side frames, and means passing on each side of but not through the head for securing said head and frames together.
60. 3. In a machine of the class described, the combination, with a pair of side frames and a tool, of a head embodying a pair of side members and a central projecting member connected therewith and bearing at each side 65 against the frames; means carried by said head for actuating the tool; and means pass-

ing transversely through the side frames at each side of the head for retaining said head in position on said side frames.

4. In a machine of the class described, the combination, with a pair of side frames and a hammer having a lifting-board, of a unitary roll-carrying head embodying a pair of side members and a central member integrally connected therewith and having an aperture to permit the passage of the lifting-board, and means passing at each side of but not through the head for retaining said head in position on the side frames.

5. In a machine of the class described, the combination, with a pair of side frames and a hammer having a lifting-board, of a unitary roll-carrying head embodying a pair of side members and a central member integrally connected therewith and forming a side abutment for said side frames, and means passing outside of but not through the head for securing said head in position.

6. In a machine of the class described, the combination, with a pair of side frames and a hammer having a lifting-board, of a unitary roll-carrying head embodying a pair of side members and a central member integrally connected therewith and having an aperture to permit the passage of the lifting-board; means for retaining said head in position on the side frames; and bolts passing on each side of but not through the head for clamping said head in position between said side frames.

7. In a machine of the class described, the combination, with a pair of uprights having rabbeted top portions, of a head having a depending apertured member provided with side projections located between said uprights, said head also having recesses to receive and fit upon the uprights; a hammer; and means carried by said head for raising and releasing said hammer.

8. In a machine of the class described, the combination, with a pair of uprights having rabbeted top portions, of a head having a depending apertured member integral therewith provided with side projections located between and fitted against the shoulders formed by said rabbeted portions of the uprights; a hammer; and means carried by said head for raising and releasing said hammer.

9. In a machine of the class described, the combination, with a pair of vertical uprights having rabbeted top portions, of a head provided with an apertured depending member with side flanges fitted against the shoulders of the rabbeted portions of said uprights, said head also having ways or recesses to receive the top portions of the uprights; a pair of rolls mounted in bearings carried by said head, one of said rolls carrying an eccentric; a hammer; a lifting-board carried thereby; and means for actuating the roll carrying the eccentric, to release said hammer.

10. In a machine of the class described, the

combination, with the usual lifting-board, of a head having bearings to receive said rolls; a pair of uprights having top portions fitted in recesses of the head; side flanges projecting from the head and bearing against the shoulders of the rabbets in the uprights; hinged caps connected to the head; and a

hammer having a strap adapted to be engaged and lifted by said rolls, substantially as and for the purpose specified.

TREDERIC C. BILLINGS.
